(57) **CLAIM**

The ornamental design for a mountable card assembly, as shown and described.

DESCRIPTION

FIG. 1 is a perspective view of a first embodiment of a mountable card assembly of the present invention wherein the

mountable card assembly of this embodiment includes a mountable portion and a card portion;
FIG. 2 is a front view of the mountable card assembly of FIG. 1;
FIG. 3 is a rear view of the mountable card assembly of FIG. 1 showing a number of coupons in dash-dot-dot-dash broken lines;
FIG. 4 is a top side elevational view of the mountable card assembly of FIG. 2;
FIG. 5 is a bottom side elevational view of the mountable card assembly of FIG. 2;
FIG. 6 is a right side elevational view of the mountable card assembly of FIG. 2;
FIG. 7 is a left side elevational view of the mountable card assembly of FIG. 2;
FIG. 8 a perspective view of a second embodiment of the mountable card assembly of the present invention wherein the mountable card assembly of this embodiment includes a mountable portion, a first card portion, and a second card portion;
FIG. 9 is a front view of the mountable card assembly of FIG. 8;
FIG. 10 is a rear view of the mountable card assembly of FIG. 8 showing a number of coupons in dash-dot-dot-dash broken lines;
FIG. 11 is a top side elevational view of the mountable card assembly of FIG. 9;
FIG. 12 is a bottom side elevational view of the mountable card assembly of FIG. 9;
FIG. 13 is a right side elevational view of the mountable card assembly of FIG. 9;
FIG. 14 is a left side elevational view of the mountable card assembly of FIG. 9;
FIG. 15 a perspective view of a third embodiment of the mountable card assembly of the present invention wherein the mountable card assembly of this embodiment includes a mountable portion, a first card portion, and a second card portion;

FIG. 16 is a front view of the mountable card assembly of FIG. 15;
FIG. 17 is a rear view of the mountable card assembly of FIG. 15 showing a number of coupons in dash-dot-dot-dash broken lines;
FIG. 18 is a top side elevational view of the mountable card assembly of FIG. 16;
FIG. 19 is a bottom side elevational view of the mountable card assembly of FIG. 16;
FIG. 20 is a right side elevational view of the mountable card assembly of FIG. 16;
FIG. 21 is a left side elevational view of the mountable card assembly of FIG. 16;
FIG. 22 is a perspective view of a fourth embodiment of the mountable card assembly of the present invention wherein the mountable card assembly of this embodiment includes a mountable portion, a first card portion, and a second card portion;
FIG. 23 is a front view of the mountable card assembly of FIG. 22;
FIG. 24 is a rear view of the mountable card assembly of FIG. 22 showing a number of coupons in dash-dot-dot-dash broken lines;
FIG. 25 is a top side elevational view of the mountable card assembly of FIG. 23;
FIG. 26 is a bottom side elevational view of the mountable card assembly of FIG. 23;
FIG. 27 is a right side elevational view of the mountable card assembly of FIG. 23; and,
FIG. 28 is a left side elevational view of the mountable card assembly of FIG. 23.
The elements shown in dash-dot-dot-dash broken line represent coupons and form no part of the claimed design. The evenly spaced broken lines represent perforations forming part of the claimed design.
